UNITED STATES PATENT OFFICE.

GEORGE WASHINGTON STEGALL, OF PARIS, TENNESSEE.

CATTLE-GUARD.

SPECIFICATION forming part of Letters Patent No. 786,171, dated March 28, 1905.

Application filed September 20, 1904. Serial No. 225,195.

To all whom it may concern:

Be it known that I, GEORGE WASHINGTON STEGALL, a citizen of the United States, residing at Paris, in the county of Henry and State 5 of Tennessee, have invented certain new and useful Improvements in Cattle-Guards; and I do declare the following to be a full, clear, and exact description of the invention, such as will enable others skilled in the art to which it 10 appertains to make and use the same.

My invention is an improvement upon those cattle-guards for railroad-tracks which are designed to prevent the encroachment of animals at fence-crossings and which comprise 15 sheet-metal strips formed with rows of teeth struck up from the strips.

One object of my invention is to provide a cattle-guard in which the sheet-metal strips can be made continuous and adapted to seat 20 upon and fit between the ties and the intermediate supports for the strips.

Another object of my invention is to provide a cattle-guard in which the sheet-metal strips can be made with rows of teeth located 25 at different elevations between and above the ties and the intermediate supports for the strips.

Another object of my invention is to provide a cattle-guard in which the sheet-metal strips can be made with depressed parts at 30 regular intervals, from which the rows of teeth project longitudinally and upwardly.

Another object of my invention is to provide a cattle-guard in which the sheet-metal strips are so formed as to interlock with the 35 middle tie and intermediate supports.

With these and other objects in view for the improvement of such cattle-guards my invention consists in novel features of construction, 40 as hereinafter described and claimed.

In order that my invention may be fully understood, I will proceed to describe it with reference to the accompanying drawings, in which—

45 Figure 1 is a plan view of a section of railroad-track located at a crossing and showing my improved cattle-guard applied thereto. Fig. 2 is a side elevation thereof. Fig. 3 is a detail plan view of the central part of the 50 same. Fig. 4 is a detail section taken on the

line 44 of Fig. 3. Fig. 5 is a detail plan view of a fragment of a depressed part.

10 represents the rails, and 11 the ties, of a part of an ordinary railroad-track located at a fence-crossing.

12 represents intermediate supports located between the ties, having their tops inclined toward the middle tie 11. Upon these ties and supports I place my improved guard, which comprises a pair of inner strips 13 and a pair 60 of outer strips 14. Each of these strips is preferably made of solid sheet metal, such as wrought iron or steel, of about one-eighth of an inch in thickness, twenty-six inches in width, and from six to eight feet in length, 65 and they are each formed with series of transversely-arranged depressed parts of acute-angle shape in cross-section and extending in opposite directions toward the end of the strip. Each depressed part has, therefore, a vertical 70 wall 15 and an inclined body 16, provided with a plain part 17, secured to the inclined faces of the supports and end ties.

18 represents sunken and elevated rows of 75 teeth of preferably triangular shape struck up from the body of each depressed part and preferably curved toward the ends of the strip, while 19 is a row of teeth, also preferably of triangular shape and struck up from the vertical wall of each depressed part and 80 extending in a longitudinal direction.

20 is the central part of the strip, which caps the top of the middle tie and is formed with two rows of vertically-arranged staggered 85 teeth 21 struck up from the central part.

It will be seen that the central part and the vertical walls of the adjacent depressed parts provide a rigid interlock between the strip and the middle tie, while the vertical walls of the other depressed parts fit against the front 90 sides of the intermediate supports.

It will be understood that the description of one strip applies to all the other strips, as they are similar in construction.

The dimensions of the teeth of the depressed parts may be varied at will; but I prefer to make them approximately four inches long by two and one-half inches wide at the base, leaving a space of about two inches between. The teeth of the central part are preferably 100

about three inches long and two and one-half inches wide at the base and two inches apart.

Among the advantages arising from the construction of my sheet-metal strips it will be seen that they can be readily applied and removed and are firmly held between the ties and intermediate supports by the depressed parts. The rows of teeth projecting in different directions and at different elevations provide a more perfect obstruction than those strips in which the points of the teeth are located approximately in the same plane.

Having thus described my invention, the following is what I claim and desire to secure by Letters Patent:

1. A cattle-guard strip, made of sheet metal and formed with series of transversely-arranged depressed parts, each having a row of longitudinally-extending teeth, a sunken row of upwardly-extending teeth in the body, and an elevated row of teeth.

2. A cattle-guard strip, made of sheet metal, and formed with series of transversely-arranged depressed parts, each having a row of longitudinally-extending teeth, a sunken row of upwardly-extending teeth in the body, an elevated row of teeth at the front, and a plain part located between the longitudinally-extending and the elevated rows of teeth.

3. A cattle-guard strip, made of sheet metal, and formed with a central part having rows of vertically-arranged teeth, and series of transversely-arranged depressed parts, extending in opposite directions from the central part, each having a row of longitudinally-extending teeth, a sunken row of upwardly-extending teeth in the body, an elevated row of teeth, and a plain part located between the longitudinally-extending and elevated rows of teeth.

4. A cattle-guard strip, made of sheet metal, and formed with series of transversely-arranged depressed parts, of acute-angle shape in cross-section, each having a row of longitudinally-extending teeth struck up therefrom, a sunken row of upwardly-extending teeth struck up from the body, and an elevated row of teeth struck up therefrom.

5. A cattle-guard strip, made of sheet metal, and formed with series of transversely-arranged depressed parts, of acute-angle shape in cross-section, each having a row of longitudinally-extending teeth struck up therefrom, a sunken row of upwardly-extending teeth struck up from the body, an elevated row of teeth struck up therefrom, and a plain part located between the longitudinally-extending and elevated rows of teeth.

6. A cattle-guard strip, made of sheet metal, and formed with a central part having rows of vertically-arranged teeth struck up therefrom, and series of transversely-arranged depressed parts of acute-angle shape in cross-section and extending in opposite directions from the central part, each having a row of longitudinally-extending teeth struck up therefrom, a sunken row of upwardly-extending teeth struck up from the body, an elevated row of teeth struck up therefrom and a plain part located between the longitudinally-extending and elevated rows of teeth.

7. The combination, with the ties and the rails supported upon the ties, of the intermediate supports having inclined tops, and a cattle-guard strip, made of sheet metal, and formed with a central part having rows of vertically-arranged teeth and located upon the middle tie and series of transversely-arranged depressed parts located between the ties and supports and extending in opposite directions from the central part, each having a row of longitudinally-extending teeth, a sunken row of upwardly-extending teeth in the body, an elevated row of teeth, and plain parts located between the longitudinally-extending and elevated rows of teeth and seating upon the inclined tops of the intermediate supports and end ties.

In testimony whereof I affix my signature in presence of two witnesses.

GEORGE WASHINGTON STEGALL.
